ATTACHMENT FOR PILE DRIVERS

William Curtis Collyer, Palo Alto, Calif., assignor
to Ingersoll-Rand Company, New York, N. Y.,
a corporation of New Jersey

Application September 4, 1942, Serial No. 457,275

3 Claims. (Cl. 61—76)

This invention relates to pile driving devices, and more particularly to a pile driver of the type that constantly rests upon a pile during the driving thereof and interlockingly engages the pile to retain the pile driver and the pile in the correct operative relationship with each other.

One object of the invention is to enable the pile receiving portion of the driver to be readily and accurately adjusted to accommodate piles of different thickness.

Other objects will be in part obvious and in part pointed out hereinafter.

In the drawing accompanying this specification and in which similar reference numerals refer to similar parts,

Figure 1 is an elevation, partly in section, of so much of a pile driver as will serve to illustrate the invention and a practical application thereof,

Figure 2 is a side elevation of the pile driver,
Figure 3 is a transverse view taken through
Figure 1 on the line 3—3, and

Figure 4 is a perspective view of a detail.

Referring to the drawing, 20 designates, in general, a pile driver and 21 a pile upon which the pile driver is arranged. Only the front end of the cylinder 22 of the pile driver is shown and said cylinder is secured to a front head 23 by bolts 24 and contains a reciprocatory piston 25 for driving the pile 21.

The cylinder 22 and the front head 23 are aligned with respect to each other by a sleeve 26 that extends part way into the opposed ends of each and serves as a guide for the stem 27 of an anvil block 28 that seats upon the pile 21 for transmitting the blows of the piston 25 to the pile. The anvil block is additionally guided by a bushing 29 in the front head 23 and has a pointer 30 on its front end to penetrate the end of the pile for retaining the pile driving mechanism in the correct driving relationship therewith.

The anvil block 28 is capable of free reciprocatory movement within the bushing and in order to prevent ejection of the anvil block from the front head stop members 31, shown as being in the form of plates, are seated against the forward end surface of the front head to extend into the plane of movement of the anvil block. The stop members 31 are fastened to the front head by bolts 32 and have tongues 33 that extend into grooves 34 on the end surface of the front head to prevent transverse movement of the stop members with respect to each other.

In accordance with a well known practice, means are provided to define a guideway 35 at the

forward end of the pile driver to receive the end of the pile 21 and to cooperate therewith for retaining the pile driver on the pile. To these ends a pair of guide brackets 36 are arranged on the forward ends of the stop member 31 and secured to the front head by the bolts 32. The guide brackets 36 are of angular shape, each bracket having a leg 37 that seats against a stop member 31 and a forwardly extending leg 38 at right angles thereto to form the bounding surface for the guideway 35. The legs 37 and 38 are suitably braced by ribs 39 and, as a preferred arrangement, the legs 37 are of such length that they will extend well beyond the outer surfaces of the stop members 31 to provide steps 40 upon which the operator may stand to press the pile driving mechanism against the work.

Inasmuch as pile drivers of the type to which the present invention pertains are used for driving piles of different thickness it is essential that the guide brackets 36 be conveniently adjustable relatively to each other to vary the width of the guideway 35. It is, moreover, desirable that such adjustments may be made quickly and with certainty so that only a minimum amount of time will be required to determine the correct positions of the brackets for a given width of the guideway and to assure that the guideway will be in substantial alignment with the anvil block. To this end the holes 41 in the guide brackets, through which the bolts 32 extend, are made of oblong shape and of suitable length to permit of a wide range of guiding positions for the guide brackets, and on the opposed surfaces of the stop members 31 and the guide brackets are groups of serrations 42 and 43 defining equally spaced ribs to engage each other in the various positions in which the guide brackets may be placed. In the assembled positions of the parts the serrations of the stop members and the guide brackets are drawn tightly into engagement with each other by the bolts 32 so that the guide brackets 36 will be anchored firmly to the front head.

Preferably the entire front end of each stop member 31 is serrated and the ends of the serrations 42 preferably coincide with the end surfaces of the stop members 31. The serrations on the guide brackets also extend from end to end thereof so that their ends are readily visible and the said serrations 43 are so positioned that the innermost one of each group is located an equal distance from the guiding surface of the leg 38. Owing to this arrangement, a wide guideway 35 may be readily defined by placing the innermost serrations on the guide brackets

in registry with the corresponding serrations on the stop members, and when the guide brackets are thus positioned the guideway 35 will be in approximate alignment with the percussive element of the pile driver.

Similarly, if it be desired to form a guideway of smaller width the guide brackets may be positioned on the stop members in such wise that one or more serrations of each guide bracket will lie inside of the inner surfaces of the stop members. Thus, as will be readily apparent, in each instance in which the guide brackets are shifted in equal degree, as indicated by the number of exposed serrations on the guide brackets, the guideway will be correctly positioned so that a pile extending into it will be in substantially true alignment with the percussive element of the pile driver.

I claim:

1. In a pile driver, the combination of a percussive tool having a casing and a reciprocatory driving element therein, a pair of guide brackets on the casing to define a guideway in the plane of movement of the percussive element and each guide bracket being adjustable relatively to the other bracket to vary the width of such guideway in equal degree relatively to the plane of movement of the driving element, and groups of serrations on opposed surfaces of the casing and the guide brackets extending from end to end of such surfaces to cooperate with each other and being visible at their ends for indicating the degree of adjustment of the guide brackets with respect to each other and with respect to the axis of the percussive element.

2. In a pile driver, the combination of a percussive tool having a casing and a reciprocatory driving element therein, stop members on the casing extending into the opposite sides of the plane of movement of the driving element, adjustable guide means seating against the ends of the casing for defining a guideway to receive an article to be driven and hold the percussive tool in driving relationship with such article,
- 5 means for securing the guide means to the casing, and serrations on opposed surfaces of the stop members and the guide means extending from end to end of such surfaces and interlocking engaging each other to prevent shifting of the guide means on the casing transversely of such guideway.
- 10 3. In a pile driver, the combination of a percussive tool having a casing and a reciprocatory driving element therein, guide members on the opposite sides of the casing to define a guideway in the plane of movement of the percussive element and each member being adjustable transversely of the percussive element to vary the width of such guideway in equal degree on
- 20 the opposite sides of the plane of movement of the percussive element, spaced ribs on the guide means and on the end of the casing interlockingly engaging each other in the different positions of the guide means on the casing to
- 25 prevent accidental shifting of the guide means relatively to the casing and to determine the positions in which the guide means may be placed upon the casing, and a step portion on the guide means.
- 30
